REFRIGERATING APPARATUS

Frank W. Andrews, Dayton, Ohio, assignor, by
mesne assignments, to General Motors Corpora-
tion, a corporation of Delaware

Application September 28, 1927, Serial No. 222,653
Renewed July 12, 1934

4 Claims. (Cl. 62—126)

This invention relates to a novel construction of evaporators for refrigerating apparatus.

One of the objects of the invention is to provide an improved evaporator which is easily and cheaply constructed.

Another object of the invention is to provide an evaporator which is smooth and readily cleaned, and of pleasing appearance.

Another object is to provide an improved evaporator having an enclosure for ice-freezing receptacles which freezes ice quickly.

Further objects and advantages of the present invention will be apparent from the following description, reference being had to the accompanying drawings, wherein a preferred form of the present invention is clearly shown.

In the drawings

Fig. 1 is an end view, partly in elevation and partly in section of one form of evaporator constructed in accordance with my invention;

Fig. 2 is a side elevation of the evaporator shown in Fig. 1;

Fig. 3 is a perspective view of another form of evaporator;

Fig. 4 is a section on the line 4—4 of Fig. 3;

Fig. 5 is a section on the line 5—5 of Fig. 4;

Fig. 6 is a section on the line 6—6 of Fig. 3; and

Fig. 7 is a perspective view of my improved evaporator in a conventional refrigerator cabinet.

Evaporators of the type including a header forming a reservoir for liquid refrigerant and depending loops of pipe connected to the header for enclosing an ice making receptacle and for circulating refrigerant have been known heretofore and are exemplified by the patent to Osborn, No. 1,556,708, October 13, 1925. Objections to such evaporators are first, that they are very expensive to manufacture, second that they are difficult to clean, and third, that they are rather unsightly when placed in a refrigerator cabinet, and for the latter reason it has been customary to conceal the evaporators in refrigerator cabinets by a special lining or partition. My invention is concerned, among other things, with eliminating the above-mentioned disadvantages.

Referring to Figs. 1 and 2, I construct an evaporator entirely of sheet metal which permits the evaporator to be formed by punching and stamping operations which are very economical to carry out. The evaporator includes a generally cylindrical header 10 which forms the reservoir for liquid refrigerant and which is adapted to contain the float valve, not shown, for controlling admission of refrigerant thereto. Depending from and connected to the header are

two hollow walls 11 which circulate the refrigerant and which define a sharp freezing space or compartment 12 adapted to receive ice-making receptacles which may be supported on brackets 12a secured to the walls. The evaporator structure includes a generally U-shaped member 13 formed of sheet metal and a second generally U-shaped member 14 also formed of sheet metal. It will be noticed that the bridges of U's include mutually convex portions 13a and 14a, 10 which when placed together form the substantially cylindrical header. The two sheets are joined together in spaced relation so that their vertical portions form the hollow walls 11 for circulating the refrigerant. This may be conveniently accomplished simply by bending one of the sheets along its edges, as indicated at 14b in Fig. 1, and welding the two sheets together. The header is closed at one end by a plate 15 welded to the sheets 13 and 14 and is left open at 20 the other end to enable a float valve to be inserted in the header. A flange 16 is welded to the open end of the header to receive a closure, which latter may carry the float valve.

It will be noticed that the walls 11 are flat, and accordingly some means is necessary to hold the two sheets together against pressure within the walls. For this purpose I provide a number of tie means distributed throughout the walls, which may be bolts or rivets 17, passing through and welded to each of the plates as at 18.

I may also form the evaporator with the hollow walls meeting at the bottom in order to enclose the freezing space completely. Such an evaporator is shown in Fig. 3. In this construction I may employ cylindrical header 30 formed of sheet metal, one end of which may be closed in any suitable manner. The other end of the header is provided with an in-turned flange 31 for receiving a front plate 32. (See Fig. 7). 40 This flange is also formed of thin sheet metal. A pair of generally U-shaped plates 33 and 34 are secured together in spaced relation and joined at their edges to form a hollow U-shaped wall, as shown in the drawings. This wall is left open 45 at its two ends 35 and 36 and the ends are welded along the length of the header. Along the lines where the walls are joined to the header, and between the sheets 33 and 34, the header is provided with a series of holes 37 to establish communication between the header and the walls. Also at the points where the walls join the header, the sheet 33 is bent outward to form flanges 38 by which the evaporator may be supported in a refrigerating cabinet. Preferably the 55

sheet 33 is provided with corrugations 40 extending in the direction of its length, while sheet 34 has a few corrugations 41 transverse to its length but is otherwise generally flat. The two sheets 5 may be spot-welded together at points along the lines where the corrugations 40 of sheet 33 touch sheet 34. The spot-welds are indicated by 42 and form the tie-means for holding the two sheets together against pressure within the walls. 10 The spaces between the corrugations 40 and the sheet 34 forming channels or ducts 45 for circulating refrigerant. The transverse corrugations 41 upon the sheet 34 are adapted to support shelves 46 on which ice-making receptacle 48 may rest. These corrugations being hollow, and communicating with the interior of the hollow walls, thus enable refrigerant to be circulated within them and accelerate the freezing of the ice within the ice-freezing receptacles placed on the shelves. 15 20 If desired, the back of the freezing space may be closed by a cover plate not shown.

For the sake of appearance I prefer to coat the entire evaporator structure with vitreous enamel and for this purpose it is necessary to bake the entire structure at high temperature. It is essential to the successful coating and baking of a thin sheet metal structure that the thickness of the metal be substantially uniform in order to insure uniform heating and cooling of the structure throughout. Consequently, the flange 31 for supporting the front closure plate must be of thin sheet metal substantially the same as the rest of the structure. However, such closure plates are usually bolted to the header and are ordinarily heavy, due to the weight of valves mounted on them. It is impractical to bolt a heavy closure plate to a thin sheet metal flange. Therefore, I provide a re-enforcing means within the header which is sufficiently heavy to enable 30 the closure plate to be securely bolted to it. It is essential that this re-enforcing means be removed during the baking operation, for the reasons mentioned above. To facilitate its removal I form the re-enforcing means of a pair of semi-circular members 51 and 52, each of which can be passed into the opening in the flange 31 and which when placed together behind the flange form a re-enforcing ring for supporting the front closure plate. The re-enforcing ring is provided 40 with bolt holes 53 and the flange 31 is clamped between the re-enforcing ring and the front plate 32. I do not wish to be limited to a pair of semi-circular re-enforcing members, as other means which provides a substantially continuous re-enforcing for the flange 31 and which is removable through the opening, may be used within the 45 scope of my invention.

By referring to Fig. 7 it will be seen that I have

provided a form of evaporator which has a smooth surface and which presents a neat appearance when placed in a refrigerator cabinet. The smooth surface facilitates cleaning of the evaporator and thus promotes sanitation while 5 the neat appearance of the device allows the usual linings or partitions to be dispensed with entirely.

While the form of embodiment of the present invention as herein disclosed, constitutes a preferred form, it is to be understood that other forms might be adopted, all coming within the scope of the claims which follow:

What is claimed is as follows:

1. An evaporator for refrigerating apparatus 15 including a header forming a reservoir for liquid refrigerant, and a plurality of sheets integrally united to the header and to each other to form hollow walls for circulating refrigerant, one or more of the sheets projecting outwardly from the 20 header at the point of attachment thereto to form flange means for supporting the evaporator.

2. An evaporator for refrigerating apparatus adapted to be coated with vitreous enamel and baked at high temperature comprising in combination, a header open at one end and a plurality of hollow walls for circulating refrigerant, said header and walls being constructed entirely of thin sheet metal, an inwardly projecting flange at the open end of the header adapted to receive 30 an end closure for the header, and rigid means within the header for reinforcing said flange entirely around its periphery, said means being removable thru the opening.

3. An evaporator for refrigerating apparatus 35 adapted to be coated with vitreous enamel and baked at high temperature comprising in combination, a circular header open at one end, and a plurality of hollow walls for circulating refrigerant, said header and walls being constructed 40 entirely of thin sheet metal, an inwardly projecting circular flange at the open end of the header adapted to have an end closure for the header bolted thereto, and a pair of semi-circular rigid members for reinforcing the flange within 45 the header.

4. An evaporator for refrigerating apparatus including a header forming a reservoir for liquid refrigerant, spaced sheet metal plates having their edges sealed together and having the ends 50 thereof united to said header for circulating refrigerant from the header to the chamber formed by the metal plates, the end of at least one of the plates projecting outwardly from the header near the point of attachment thereto to form 55 flange means for supporting the evaporator.

FRANK W. ANDREWS.
